E. J. CARROLL

CENTRIFUGAL EXTRACTOR

Filed Jan. 25, 1923

UNITED STATES PATENT OFFICE.

EMIL J. CARROLL, OF NORWOOD, OHIO, ASSIGNOR TO THE AMERICAN LAUNDRY MACHINERY COMPANY, OF CINCINNATI, OHIO, A CORPORATION OF OHIO.

CENTRIFUGAL EXTRACTOR.

Application filed January 25, 1923. Serial No. 615,437.

This invention relates to centrifugal extractors, such as are used for extracting water or any liquid or moisture from other materials, such as water from wet garments or fabrics in laundries or cleaning fluids in dry cleaning plants. The invention more particularly relates to extractors of the swinging curb type, where both the curb and basket have oscillating movement to 10 adapt the rotating spindle to assume new positions due to unbalanced loads or for other reasons. The invention is an improvement on the extractor shown, described and claimed in my prior application for 15 extractor control, filed July 22, 1921, Serial No. 486,717.

One important object of the invention is to improve the bearings for the basket spindle or shaft to avoid cramping and minimize wear, especially that due to shaft 20 deflection produced by unbalanced loads either contained in the basket or the result of unequal distribution of the metal in the rotating parts. More particularly the invention aims to simplify and improve the bearing structure and avoid otherwise harmful effects of shaft deflection and unbalanced load by mounting the basket spindle in upper and lower bearings arranged 25 to properly accommodate themselves to any lateral deflection of the shaft, the intermediate portion of which is allowed to go and come as it pleases.

Another object of the invention is to 30 provide a motor drive for the spindle of a basket mounted as before stated, the relatively rotating and stationary parts of said motor being provided with maximum clearance therebetween, so that the spindle can 35 be directly driven by a motor but without harm to the motor parts by shaft deflection or for other causes.

A further object of the invention is to 40 provide an extractor of the character described in which the basket and curb together, or as a unit, are mounted to oscillate from an upper point of suspension as a true center, or by universal joint movement, so that all the movable parts of the apparatus 45 are free to assume proper axes of rotation and thereby minimize all inherent dangers in mechanism of this kind.

A further object of the invention is to 50 improve the construction and arrangement 55 of the bearings at the upper and lower ends

of the rotating spindle so that lubrication thereof is simplified and danger of a dry bearing is minimized.

A further object of the invention is to 60 provide an extractor embodying direct motor drive of the kind described with suitable means for relatively adjusting the relatively stationary and rotatable motor parts lengthwise of the motor axis to compensate for wear and maintain the highest efficiency. 65

Further objects of the invention are in 70 part obvious and in part will appear more in detail hereinafter.

In the drawings, Fig. 1 represents a 75 sectional elevation from front to rear of one embodiment of the invention, the guarding gate or door being shown in elevation and in its guarding position; and Fig. 2 is a similar view of a portion of the machine omitted from the lower right hand corner in Fig. 1.

The extractor shown in the drawings 80 comprises a suitable curb or casing 1 forming part of a frame 2 in which is the usual foraminous or perforated rotating basket 3 carried by a spindle or shaft 4 journalled in the curb frame as will more fully appear. The parts just mentioned are mounted to have oscillating movement as a unit about a fixed point. For this purpose the curb frame 2 is provided with a rigid semi-spherical head 5 resting in a semi-spherical socket carried by a fixed support 6. The latter is rigidly attached to any supporting structure and may for example, be fastened 85 to the ceiling of the building or, as illustrated, may be in the form of a bracket attached to a suitable frame 7 having a base 8 resting on the floor or other support. The ball 5 and its socket permit the curb frame 90 and parts supported thereby to swing in any direction or assume and accept new positions to compensate for unbalanced load or because of other forces, such as the gyroscopic effect, etc.

In extractors of this type, where both 95 curb and basket swing, considerable difficulty has been experienced with the bearings for the rotating basket spindle or shaft, the wear on which is ordinarily severe. Investigation has shown that much of this difficulty is due to the cramping effects at the bearing sleeves due to shaft deflection. In other words, an unbalanced load, whether it be due to material placed in the basket or 100 105 110

because of unequal distribution of metal, or for other causes, acts like the balls of the well known Porter ball governor and pulls or bends the shaft out of a straight line, thereby cocking askew those portions of the shaft at the bearings. Not only does this action produce a harmful effect upon rigid bearings but it also heretofore has prevented the use of direct motor drive to the spindle, because the clearance between the rotating and stationary motor parts, in ordinary motors, is purposely made so small that shaft deflection produces contact between such parts and injures the motor.

To avoid the objections stated, I preferably so arrange the spindle bearings as to enable its ends to assume askew positions in the frame or curb parts in which they rotate without bodily displacement relative thereto and therefore without effect upon the operation of the bearings, and I also provide a special motor having maximum clearance between its stationary and rotating parts. In other words, I arrange the bearings and the motor to take account of shaft deflection and then allow the shaft to go and come, as regards deflection, where it will.

In the arrangement shown in the drawings for this purpose the spindle 4 is provided at its upper end with suitable bearings, such as the Hyatt roller bearings 9, in a ball member 10 mounted in a semi-spherical socket member 11 carried by the curb frame 2 and closed by a ball socket sleeve 12 held in place by a closing cap 13.

At the lower end of the spindle the curb carries a fixed casing member 14 of tubular form and provided with a semi-spherical seat 15 for the ball portion 16 of a bearing sleeve 16^a. Said casing is closed at its top by a suitable cap 17. The bearing sleeve at its lower end has secured thereto a step casting 18 forming a seat for the usual step bearing disks or buttons 19.

The curved dot and dash line A, Fig. 1, conventionally represents and exaggerates a position the shaft assumes under unbalanced load, its central portion being deflected laterally so that the shaft as a whole is bent to curved form. Obviously the two universal joints between the bearing members for the shaft and the relatively stationary curb and curb frame parts in which they are mounted allow such shaft deflection without in any way affecting the bearing conditions and particularly avoid cramping or binding in the bearings. Any slight shortening of the shaft vertically by bending is taken up by longitudinal sliding motion of the shaft in the upper bearing, but such shortening effect is usually so slight as to be negligible.

This arrangement of universal or self adapting mounting for the upper and lower ends of the extractor spindle also simplifies the lubrication problem. For example, in

the upper bearing 20 represents a pair of threaded rings screwed into the ball 10 and serving not only to adjust the Hyatt rollers but to also carrying packing rings 21 to prevent escape of lubricant between the rotating sleeve 22 carried by the spindle and the said relatively stationary rings. Beneath said rings the shaft carries a collar 23, the upper surface of which is inclined and directs any leaking lubricant into a stationary annular receiver 24 from which it flows by the pipe 25 to a collecting cup 26. This bearing may be lubricated with grease or other similar lubricant supplied thereto from a grease cup 27 and may be packed and the lubricant renewed as frequently as desired by merely screwing up the grease cup.

In the lower bearing the bearing sleeve 16^a is provided with a series of perforations 28 and the ball portion 16 thereof is slotted vertically, as at 29, or is provided with spiral grooves 29^a. As a result lubricant may be supplied to all bearing surfaces from a stand pipe 30 communicating with an orifice in the bottom of the casing 14, the oil flowing up around the oscillating sleeve 16^a and through the openings and channels therein to the bearing surfaces. However, with this lower bearing grease packed roller bearing may also be used similar to those at the upper end of the spindle.

The spindle is directly driven preferably by an electric motor, the parts being so arranged that the rotatable motor parts are carried by the shaft and the stationary parts thereof by the curb frame. For example, 31 represents the stationary motor casing provided with arm portions 32 rigidly secured to brackets or portions 33 of the curb frame. This stationary motor casing carries the stator or field frame 34 cooperating with the rotor or armature 35 attached to the spindle 4. In the manufacture of the motor the clearance between stator and rotor or between field and armature is made sufficient to allow for maximum shaft deflection and is calculated according to the maximum unbalanced condition to be encountered in practice. This clearance therefore is greater than is usually found in motors of this character but the structure results in gains in durability and safety arising from the inherent adaptability of the machine to unbalanced load conditions. Naturally, by increasing the shaft diameter its possible deflection under a given load decreases rapidly and in this way motor clearance may be reduced, if desired or necessary.

For the sake of efficiency, the structure may be provided with suitable means for adjusting the stator and rotor relatively to each other longitudinally of the motor axis, to enable them to be adjusted to and held in the most efficient position. The drawings show for this purpose shims 36 between the

arms 32 and curb frame parts 33. As the parts wear and the basket spindle settles down shims 36 can be inserted or taken out according to whether the arms 32 are supported beneath or above the members 33 to compensate. Any other adjusting arrangement would be suitable for the purpose.

The electrical equipment for this structure may be adapted for either A. C. or D. C. circuits and includes the necessary controlling parts to safeguard the operator against injury and insure proper working conditions. For this purpose the machine is equipped with a rising and falling guarding gate or door 40 having rollers 44 traveling on tracks 45 at the front of the machine to expose or shut off access to the basket opening. Said door is counterbalanced by weights 41 connected thereto by chains or other flexible members 42 passing over pulleys 43.

What I claim is:—

1. An extractor, comprising a frame, a rotatable basket and spindle, separated bearings for said spindle, means for preventing bodily displacement of said bearings in said frame and for permitting oscillating movement of each of said bearings therein due to spindle deflection resulting from unbalanced load and separation of the bearings, and a direct motor drive for said spindle including relatively stationary and rotating parts, the stationary part being fixed against movement relative to the frame and the rotating part being carried by said spindle, said stationary and rotating parts being relatively arranged so as to provide sufficient clearance therebetween for the maximum deflection of the spindle at the motor.

2. An extractor, comprising a frame, a rotatable basket and spindle, separated bearings for said spindle, means for preventing bodily displacement of said bearings in said frame and for permitting oscillating movement of each of said bearings therein due to

spindle deflection resulting from unbalanced load and separation of the bearings, and a direct motor drive for said spindle including relatively stationary and rotating parts, the stationary part being fixed against movement relative to the frame and the rotating part being carried by said spindle, said stationary and rotating parts being located between the separated bearings and being relatively arranged so as to provide sufficient clearance therebetween for the maximum deflection of the spindle at the motor.

3. An extractor, comprising a curb frame member suspended to oscillate in any direction from a vertical axis, a rotatable basket and spindle, separated upper and lower bearings in said member for said spindle, means whereby each of said bearings is permitted to assume an askew position in said curb member due to spindle deflection resulting from unbalanced load but without effect upon the operation of said bearings, and a direct motor drive for said spindle including relatively stationary and rotating parts, the former fixed against movement relative to the frame and the latter being carried by the spindle, said motor parts being arranged to provide sufficient clearance therebetween for maximum spindle deflection at the motor.

4. An extractor, comprising a relatively stationary support, a curb member suspended therefrom, a rotatable basket and spindle, relatively stationary and rotating motor parts carried by the curb member and spindle respectively, and means whereby the stationary motor parts may be adjusted on said curb member relative to the rotating motor parts and longitudinally of the spindle axis.

In testimony whereof I hereby affix my signature.

EMIL J. CARROLL.
